UNITED STATES PATENT OFFICE

WILLIAM WILLHEIM, OF NEW YORK, N. Y.

DESIGN FOR A TEXTILE FABRIC COLLAR OR SIMILAR ARTICLE

Application filed December 1, 1932. Serial No. 46,241. Term of patent 3½ years.

To all whom it may concern:

Be it known that I, WILLIAM WILLHEIM, a citizen of the United States of America, residing at 115 Central Park West, in the city of New York, county of New York, and State of New York, have invented a new, original, and ornamental Design for a Textile Fabric Collar or Similar Article, of which the following is a specification, reference being had to the accompanying drawing, forming a part thereof.

The figure is a plan view of a textile fabric collar showing one half of the unit of my new design. The other one half bears the same design and is arranged in opposite relation to the detailed illustration to complete the pattern. The drawing is lined to indicate shading.

I claim:

The ornamental design for a textile fabric collar or similar article as shown and described.

In testimony whereof I have signed this specification.

WILLIAM WILLHEIM.
